UNITED STATES PATENT OFFICE.

ALBERT F. MEDER, OF WHEELING, WEST VIRGINIA.

DESIGN FOR A DRINKING-GLASS.

SPECIFICATION forming part of Design No. 31,499, dated September 12, 1899.

Application filed August 12, 1899. Serial No. 727,073. Term of patent 3½ years.

To all whom it may concern:

Be it known that I, ALBERT F. MEDER, a citizen of the United States, residing at Wheeling, in the county of Ohio and State of West Virginia, have invented and produced a new and original Design for Drinking-Glasses, of which the following is a specification.

My invention relates to a new design for a drinking-glass, and is illustrated in the accompanying drawing, in which the figure is an elevation.

The leading feature of my design consists in a drinking-glass the stem of which is supported upon a base and presents a plurality of plane peripheral sides, the corners separating the sides being nicked and said stem being surmounted by a rounded bulb-like formation which merges into the frusto-conical-shaped bowl.

In said drawing the reference-numeral 1 indicates the base, and 2 the stem, having a plurality of plane sides 3, separated by nicked corners 4.

The numeral 5 indicates the enlargement at the foot of the stem, formed with grooves 6, the ridges 7 of which are nicked.

The numeral 8 indicates the rounded bulb-like formation surmounting the stem and which merges into the frusto-conical-shaped bowl 9.

My design presents a drinking-glass having a new, pleasing, and artistic appearance.

Having thus described my invention, what I claim as new, and desire to secure by Letters Patent, is—

The design for a drinking-glass substantially as herein shown and described.

In testimony whereof I have hereunto set my hand in presence of two subscribing witnesses.

ALBERT F. MEDER.
